(57) **CLAIM**

The ornamental design for sensor mounting adapter base for heavy duty vehicle rear wheel assembly, as shown and described.

DESCRIPTION

FIG. 1 is a front perspective view of the sensor mounting adapter base for a heavy duty vehicle rear wheel assembly; FIG. 2 is a rear perspective view of the sensor mounting adapter base;

FIG. 3 is a front plan view of the sensor mounting adapter base;

FIG. 4 is a rear plan view of the sensor mounting adapter base;

FIG. 5 is a left side plan view of the sensor mounting adapter base;

FIG. 6 is a right side plan view of the sensor mounting adapter base;

FIG. 7 is a top plan view of the sensor mounting adapter base; and,

FIG. 8 is a bottom plan view of the sensor mounting adapter base.

Features shown in phantom in the drawings form no part of the claimed design.
